INVENTOR

John F. Donnelly.

BY

W. J. Criswell.
ATTORNEY

UNITED STATES PATENT OFFICE.

JOHN F. DONNELLY, OF NORTH PLAINFIELD, NEW JERSEY.

HAIR CRIMPER.

Application filed June 26, 1922. Serial No. 570,821.

To all whom it may concern:

Be it known that I, JOHN F. DONNELLY, a citizen of the United States, and a resident of North Plainfield, in the county of Somerset and State of New Jersey, have invented certain new and useful Improvements in a Hair Crimper, of which the following is a full, clear, and exact specification.

This invention relates to a class of curling devices. It has for its object primarily to provide a crimper adapted to be used by women for facilitating the work of curling the hair without requiring the employment of heated irons, and which is of a form whereby the strands of hair practically in entirety or the desired portions of the strands may be closely or loosely curled in a manner so that the curls or waves will be retained for considerable periods. The invention contemplates mainly the provision of two jaw members having one of their ends pivoted for being swung to and from each other in spaced relation, and on one of the members is wrapped the hair, while the other member is adapted to serve for holding the wrapped hair. A third jaw member is pivotally held to the pivot of the pair of jaw members for being swung upon one of the pair of members for also allowing the hair to be wrapped thereon, and clamping members are provided on the jaw members for releasably fastening the members together.

A further object of the invention is to provide a hair crimper of a simple, efficient and durable construction which may be made in any appropriate size.

With these and other objects in view the invention will be hereinafter more fully described with reference to the accompanying drawing forming a part of this specification in which similar characters of reference indicate corresponding parts in all the views, and will then be pointed out in the claims at the end of the description.

In the drawing, Figure 1 is a perspective view of one form of hair crimper embodying my invention with its parts swung to open positions.

Fig. 2 is a top plan of the crimper, showing the manner which hair is wrapped on one of its jaw members, and

Fig. 3 is a side view of the crimper with

its jaw members in closed positions with hair partly wrapped thereon during the curling process.

The hair crimper has a jaw member 10 which is preferably in the form of a strip of metal having one of its ends bent upwardly, as at 11, and then bent outwardly, as at 12, from one face of the strip. On the other end of the strip is an overhanging extension or substantially U-shaped member 13 which may be provided by bending accordingly the second end portion of the strip, and the arm, as 14, of the U-shaped extension member extends toward the bent part 11 of the strip as well as being spaced from the strip to provide the entrance to the U-shaped member, as at 15.

To the outwardly bent part 12 of the jaw member or strip 10 is pivoted at 16, one end of a second jaw member or strip 17. The strips 10 and 17 may be swung to and from each other in spaced parallel relation, and the strip 17 is of a length so that it may be swung under the central part of the arm 14 of the U-shaped member 13 of the strip 10. On the second end of the jaw member or strip 17 is a substantially S-shaped member or clamp 18, and the space between the lower parts of this member 18 provides a groove 19 in opposed relation to the pivot 16 of the strips 10 and 17, while the space between the upper parts of the S-shaped member 18 also provides a groove 20 for removably receiving the arm 14 of the U-shaped member 13 of the strip 10. When the arm 14 of the U-shaped member 13 of the strip 10 is positioned in the groove 19 of the S-shaped member 18, the arm 14 is releasably fastened to the S-shaped member by providing an upwardly protruding clamp member or lug, as 21, on the arm, and provided in the upper arm, as 22, of the S-shaped member is a slot, as 23, for removable insertion of the lug 21. The jaw members or strips 10 and 17 will also then be releasably locked together.

To the pivot 16 of the strips 10 and 17 is pivotally held one end of a third jaw member or flat strip 24 for being swung into lapping position on the strip 17. The strip 24 is of a length so that when swung upon the strip 17 its second end portion will be removably inserted in the groove 19 of the

S-shaped member 18 for releasably fastening the strips 17 and 24 together by frictional engagement with the walls of the groove 19.

While the crimper as thus constructed may 5 be used in the most convenient manner for curling hair, the device may be effectually employed as illustrated by swinging the jaw members 10, 17, 24 to open positions, as 10 shown in Fig. 1, and wrapping the hair, as 15 strip 25, on the strip 17, as shown in Fig. 2. The strip 24 may then be swung upon the wrapped hair and upon the strip 17, and these strips are detachably fastened together by the free end of the strip 24 being seated 20 in the groove 19 of the **S**-shaped member 18 of the strip 17. The hair may afterward be wrapped on both of the strips 17 and 24, after which the strip 10 is swung upon the wrapped hair and upon the fastened strips 25 25 17 and 24 so that the arm 14 of the **U**-shaped extension member 13 will be removably received in the groove 20 of the **S**-shaped member 18 of the strip 17 and so that the lug 21 of the **U**-shaped member will be seated 30 in the slot 23 of the **S**-shaped member. All of the jaw members or strips will then be releasably clamped for holding the wrapped hair for a suitable period in order to curl or wave the strands of hair.

35 While in the foregoing description, I have embodied the preferred form of my invention, I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

40 Having thus described my invention, I claim as new and desire to secure by Letters Patent:

1. A hair crimper, comprising a jaw member, a second jaw member having one 45 of its ends pivoted to one of the ends of the first mentioned jaw member so that both members may be swung to and from each other in spaced parallel arrangement, complemental clamp members on the second 50 ends of both jaw members for releasably fastening both jaw members together, and a third jaw member having one of its ends pivotally held to the pivot of the pair of jaw members so that the third jaw member 55 may be swung to and from lapping position on the second jaw member as well as being detachably engageable by the clamp member of said second jaw member.

2. A hair crimper, comprising two jaw 60 members having one of their ends pivoted for being swung to and from each other in spaced relation, an overhanging extension member spaced from the second end of one of the jaw members, a substantially **S**-shaped member overhanging the second end 65

of the second jaw member for removably receiving in one of its grooves the free end portion of the extension member of the first named jaw member, and complemental clamp members on said extension member and on said **S**-shaped member for releasable engagement when the jaw members are swung together. 70

3. A hair crimper, comprising two jaw members having one of their ends pivoted for being swung to and from each other in spaced relation, an overhanging extension member spaced from the second end of one of the jaw members, a substantially **S**-shaped member overhanging the second end 75 of the second jaw member for removably receiving in one of its grooves the free end portion of the extension member of the first named jaw member, complemental clamp members on said extension member and on said **S**-shaped member for releasable engagement when the jaw members are swung together, and a third jaw member pivotally held to the pivot of the pair of jaw members for being swung to and from lapping position on said second jaw member and into and out of the second groove of the **S**-shaped member of said second jaw member. 80

4. A hair crimper, comprising a strip having a bent end and having its other end curved to provide a substantially **U**-shaped member with its free arm overhanging in spaced relation the strip, a lug protruding from the free arm of the **U**-shaped member, a second strip having one of its ends pivoted to the bent end of the first named strip so that the strips may be swung to and from each other in spaced parallel positions, and an approximately **S**-shaped member formed on the other end of the second strip so that the free arm of the **U**-shaped member of the first named strip with its lug will be removably received under the free arm portion of the **S**-shaped member of the second strip and the free arm portion of said **S**-shaped member having a slot for removable engagement of the lug of the **U**-shaped member of the first named strip. 95

5. A hair crimper, comprising a strip having a bent end and having its other end curved to provide a substantially **U**-shaped member with its free arm overhanging in spaced relation the strip, a lug protruding from the free arm of the **U**-shaped member, a second strip having one of its ends pivoted to the bent end of the first named strip so that the strips may be swung to and from each other in spaced parallel positions, an approximately **S**-shaped member formed on the other end of the second strip so that the free arm of the **U**-shaped member of the first named strip with its lug will be removably received under the free arm portion of the **S**-shaped member of the second 100 strip. 110

115

120

125

130

strip and the free arm portion of said **S**-shaped member having a slot for removable engagement of the lug of the **U**-shaped member of the first named strip, and a third strip 5 having one of its ends pivotally held to the pivot of the pair of strips for being swung to and from lapping position on the second strip as well as having its other end re-

movably disposed in one of the grooves of the **S**-shaped member of said second strip. 10

This specification signed and witnessed this 24 day of June, A. D. 1922.
